(57) **CLAIM**

The ornamental design for a connector for making optical connections, as shown and described.

DESCRIPTION

FIG. 1 is a top perspective view of a connector for making connections in optical networks;

FIG. 2 is a top view of the connector of FIG. 1;

FIG. 3 is a bottom view thereof of FIG. 1;

FIG. 4 is a right side view thereof of FIG. 1;

FIG. 5 is a left side view thereof of FIG. 1;

FIG. 6 is a front view thereof of FIG. 1; and,

FIG. 7 is a rear view thereof of FIG. 1.

In FIGS. 1-7, the broken lines indicate environmental structure and form no part of the claimed design.
